HYDRAULIC-CONTROL HEAD CLOSURE

Application filed April 14, 1928. Serial No. 270,046.

The present invention relates to deep well apparatus. As is well known, high pressure oil and gas strata are encountered in deep wells during various stages of operations and the high pressures frequently result in the blowing out of a string of tools or pump apparatus in the well with serious damage to the well structure and to the surrounding property and with great danger to the operatives.

Furthermore, fires frequently arise and considerable difficulty is experienced in cutting off the admission of air to the well casing. It is therefore one of the principal objects of the present invention to provide a means for effecting the actuation of the closure plug associated with the head on the upper end of the casing. A salient object of the present invention resides in the provision of a mechanism for effecting the closing of the plug by a fluid under pressure, said mechanism including a spur gear that is operatively associated with the stem of the rotary plug arranged in the head of the casing, a sliding rack bar having meshing engagement with the teeth of the spur gear and being operable by a piston rod that carries a piston which is reciprocably mounted in a cylinder, said cylinder being provided with fluid inlet openings at the respective ends thereof to effect the movement of the piston in opposite directions to open and close the plug. A further object of the invention is to provide a hydraulic control head closure which is simple in construction, inexpensive, strong and durable and further well adapted to the purposes for which it is designed.

Other objects and advantages will become apparent during the course of the following description.

In the accompanying drawings, forming a part of this specification, and in which like numerals indicate like parts throughout the same:

Figure 1 is an elevational view in section of the hydraulic control head closure constituting our invention showing the manner in which the same is associated with the upper portion of the well casing, and

Figure 2 is a similar view taken at right

angles to Figure 1 for more clearly disclosing the cooperating toothed rack and spur gear.

In the drawings wherein for the purpose of illustration is shown the preferred embodiment of our invention, the numeral 1 designates generally the pit or working chamber constructed in the ground around the upper end of the well and extending through the bottom of the pit is the upper end of the well casing 2. The upper end of the casing has arranged thereon the usual head 3 within which is arranged the rotatable plug 4, the operating stem of which is shown at 5 in Figure 1. Usually a wrench or other similar tool is arranged on the operating stem 6 for moving the closure plug either to an open or closed position and by reason of the operator having to actuate the closure plug at a point adjacent the head 3, the operator is placed in a dangerous position in case of fire 7 and should an attempt be made to close the plug during the happening of such a contingency, there is a possibility of the operator becoming burned. We have therefore devised a means for facilitating the actuation 8 of this closure plug from a distant point and in a safe and positive manner whenever an emergency arises or in fact at any time when it is desired to either open or close the upper end of the casing of an oil or gas well.

Our improved mechanism includes a relatively large spur gear that is secured on the outer end of the stem 5 associated with the rotatable plug 4 for rotation therewith and an annular flange 7 is associated with the body of the gear inwardly of the teeth 8 for a purpose to be presently described. The actuating mechanism further includes a vertically disposed cylinder 9 that is closed at its respective ends, the lower end of the cylinder 10 being rockably supported as at 11 on a suitable bracket 11 that is secured on a supporting base 12 arranged in the bottom of the pit or working chamber 1. This cylinder is arranged adjacent the upper portion of the casing 2 and the upper end thereof terminates below the casing head 3 as clearly illustrated in the drawings. Operable within the cylinder 9 is the piston 13, the same being secured on the lower end of a piston rod 14 100

- that extends upwardly through the closed upper end of the cylinder. A pressure fluid supply pipe 15 extends into the side of the cylinder at the lower end thereof, a similar 5 pressure fluid supply pipe 16 extending into the side of the cylinder adjacent its upper end for supplying a pressure fluid to act on the piston to effect the reciprocatory movement of the same in the cylinder.
- 10 These supply pipes 15 and 16 extend from any suitable source of supply not shown. Co-operating with the teeth 8 of the spur gear 6 are the transverse gear teeth 17 arranged on the inner face of an elongated rack bar 18 that is slidably disposed between the casing 2 and the cylinder 9 and the upper end portion of this rack bar is operatively connected to the upper end of the piston rod as at 19 so that said rack bar will move vertically simultaneously with the movement of the piston rod during the reciprocatory movement of the piston 13 in the cylinder 9. An elongated rod 20 is carried by the lower end of this rack bar and is slideable through a 15 guide 21 carried by the lower portion of the cylinder 9 as shown very clearly in Figure 1. The upper portion of the rack bar is furthermore guided in its sliding movement by the L-shaped bracket shown at 22, the horizontal arm portion of which is in the form of a clamp that encircles the upper portion of the cylinder 9 as shown at 23 in Figure 2 and the vertical arm of the L-shaped bracket extends upwardly for cooperation with the 20 outer side of the rack bar 18. This vertical portion of the bracket is slotted to accommodate the connecting means between the upper end of the piston rod and the rack bar as indicated at 24 in Figure 2.
- 25 Carried by the upper end portion of the vertically disposed arm of the L-shaped bracket 22 is the yoke 25 and the arms of this yoke are disposed on opposite sides of a flanged gear 6, the free ends of the arms 30 of the yoke being bent inwardly and thence laterally and a roller 26 is carried by the inner end of each arm for engagement with the inner peripheral face of the flange 7 on each side of the gear body as indicated in 35 Figure 1 for maintaining the gear teeth 17 in meshing engagement with the teeth 8 of the gear 6. When the piston 13 is in its lowermost position in the cylinder 9, the plug 4 is in one position. Presuming that this 40 position is such that the plug permits the free flow of the oil or gas through the head into the outlet pipe 27, we will now describe the manner in which said plug 4 is moved to a closed position. A fluid under pressure 45 is delivered to the lower end of the cylinder through the supply pipe 15 and this will cause the piston 13 to move upwardly in the cylinder and simultaneously raise the piston rod 14 which action will result in the 50 upward sliding movement of the rack bar 18

and as the teeth 17 of this rack bar are in meshing engagement with the teeth 8 of the gear body 6, said gear 6 will rotate. As this gear is secured on the outer end of the stem of the rotary plug 4, the rotary plug 55 will be actuated and moved to a closed position in the casing head 3

In this manner, the upper end of the well casing may be closed from a remote point thereby obviating any necessity of an operator having to stand in the pit 1 and actuate the rotary plug to cut off the discharge of the gas or oil at the top of the well casing. A safety mechanism of this character will at 60 all times be positive and efficient in its operation and whenever it is desired to open the upper end of the casing, the cylinder is injected with a fluid under pressure that flows through the pipe 16 so that the piston 13 will move downwardly in the cylinder and simultaneously move the rack bar 18 downwardly to actuate the gear 6 and in turn move the closure plug 4 to a closed position. It is of course to be understood that any appropriate valve mechanism may be associated with the pressure fluid supply pipes. A hydraulic control head closure of the present type can be readily and easily installed without necessitating any material alterations of the parts of an oil well apparatus with which 65 said mechanism is to be associated.

While we have shown the preferred embodiment of our invention, it is to be understood that various changes in the size, shape and arrangement of parts may be resorted to without departing from the spirit of the invention and the scope of the appended claims.

What we claim is:—

1. The combination with the rotary valve in a well casing head; of means for actuating said valve, said means comprising a gear carried by the stem of said valve for rotation therewith, a toothed rack bar having meshing engagement with said gear, fluid pressure operated means for actuating the sliding toothed rack bar, said last mentioned means including a cylinder, a piston rod extending through one end of the cylinder, a piston secured on the inner end of the piston rod for reciprocatory movement in the cylinder, an operative connection between the outer end of the piston rod and the sliding toothed rack bar, and fluid pressure supply pipes communicating with the respective ends of the cylinder to control the operation of the piston therein.

2. The combination with the rotary valve in a well casing head; of means for actuating said valve, said means comprising a gear carried by the stem of said valve for rotation therewith, a toothed rack bar having meshing engagement with said gear, fluid pressure operated means for actuating the sliding toothed rack bar, said last mentioned means including a cylinder, a piston rod ex-

tending through one end of the cylinder, a piston secured on the inner end of the piston rod for reciprocatory movement in the cylinder, an operative connection between the outer end of the piston rod and the sliding toothed rack bar, and fluid pressure supply pipes communicating with the respective ends of the cylinder to control the operation of the piston therein, and guide means for the sliding toothed rack bar.

10 3. The combination with the rotary plug arranged in a well casing head, the stem of said plug extending axially through one end of the head, of means for turning said 15 plug, said means comprising a flanged gear wheel secured on the outer end of the stem for rotation with the plug, a vertically disposed sliding toothed rack bar having meshing engagement with the teeth of the gear 20 wheel, a cylinder, a piston operable within the cylinder, a piston rod slidable through the upper end of the cylinder and being connected at its lower end to the piston, an operative connection between the upper end 25 of the piston rod and the sliding rack bar, fluid pressure supply pipes communicating with the upper and lower ends of the cylinder to actuate the piston and effect operation of the sliding toothed rack bar to rotate the 30 plug, guide means for the upper and lower ends of the rack bar, a yoke carried by the upper guide means, and a flange engaging wheel carried by the yoke for engagement with the flange on the gear wheel.

35 In testimony whereof we affix our signatures.

SAMUEL S. BRADSHAW.
